(57) **CLAIM**

I claim the ornamental design for the watercraft, as shown and described.

DESCRIPTION

FIG. 1 is a front perspective view of a watercraft embodying my novel design;

FIG. 2 is a front end view thereof, the rear view being identical to the front end view;

FIG. 3 is a bottom plan view thereof;

FIG. 4 is a side elevational view thereof, the other side being identical to the side view shown; and,

FIG. 5 is a top plan view thereof.
